(57) **CLAIM**

The ornamental design for a catheter sleeve, as shown and described.

DESCRIPTION

FIG. 1 is a perspective view of a catheter sleeve showing my new design;

FIG. 2 is a bottom plan view thereof;

FIG. 3 is a front elevational view thereof;

FIG. 4 is a right side elevational view thereof;

FIG. 5 is a top plan view thereof;

FIG. 6 is a left side elevational view thereof; and,

FIG. 7 is a rear elevational view thereof.

The portions of the drawings shown in broken lines are for environmental purposes only and form no part of the claimed design.
